UNITED STATES PATENT OFFICE.

MANLY M. GILLAM, OF NEW YORK, N. Y.

ACTUATING MECHANISM FOR ADVERTISING DEVICES.

SPECIFICATION forming part of Letters Patent No. 554,926, dated February 18, 1896.

Application filed October 15, 1895. Serial No. 565,753. (No model.)

To all whom it may concern:

Be it known that I, MANLY M. GILLAM, a citizen of the United States, residing at the city of New York, in the county of New York and State of New York, have invented certain new and useful Improvements in Actuating Mechanism for Advertising Devices, of which the following is a specification.

My invention has relation to actuating mechanism for advertising devices of the class wherein a sign carrying two or more descriptive faces is adapted to be rotated; and it relates particularly to the arrangement and construction of mechanism for actuating a sign.

The principal objects of my invention are, first, to provide a simple, durable, and inexpensive mechanism for rotating an advertising-sign; second, to provide in such a mechanism an electromagnet the armature of which is adapted periodically to rotate the sign, and, third, to provide in such a mechanism means whereby, during operation of the armature and an arm carried thereby, the magnet is alternately magnetized and demagnetized.

My invention consists of an actuating mechanism for rotating an advertising-sign constructed and arranged in substantially the manner hereinafter described and claimed.

The nature, characteristic features, and scope of my invention will be more fully understood from the following description, taken in connection with the accompanying drawings, forming part hereof, and in which—

Figure 1 is an end elevational view of an apparatus for rotating a sign embodying features of my invention and illustrating an electromagnet and an armature adapted to control the actuation of the sign. Fig. 2 is a side elevational view of the apparatus; and Fig. 3 is a side elevational view, enlarged, of the lower end of the contact making and breaking strip, illustrating the successive positions assumed by the same during the movement of the armature-controlled arm of the device.

Referring to the drawings, *a* represents the end and *e* the longitudinal descriptive faces of a rotatable sign. The sign is supported by means of a shaft *c* in a bracket or standard *d*, so that said sign may rotate therein. The shaft *c* of the sign is supported in the arms

of a standard *d*, and to the shaft is keyed or otherwise secured a disk *n*, provided on its periphery with a number of stop-pins *n'*, corresponding in number with the faces of the sign, which in the present instance are four, as illustrated. On the face of the disk *n* are a corresponding number of actuating-pins *n*². Above the periphery of the disk *n* and resting thereon is a gravity-pawl *n*³, adapted to abut against one of the stop-pins *n'* to prevent the rotation of the disk *n* in one direction. Resting on the pins *n*² is a hook-shaped arm *n*⁴, which is secured at its lower end to a lever-arm *n*⁵, which is pivoted to an upright *n*⁶ of the standard *d*, and normally held upward, as indicated in Fig. 7, by the spring *n*⁷. The lever-arm *n*⁵ carries the armature *n*⁸ of an electromagnet *n*⁹, and the said arm *n*⁵ is adapted to be depressed by the electromagnet *n*⁹, when it is energized, against the tension of the spring *n*⁷. Below the disk *n* is located a stop-pawl *n*¹⁰, connected by a wire or link *n*¹¹ to the lever-arm *n*⁵ and controlled by said link and lever-arm.

When the electromagnet *n*⁹ is energized and the lever-arm *n*⁵ is depressed, the hook-shaped arm *n*⁴ will strike against one of the pins *n*² and carry the disk *n* in a forward direction. Directly after the thrust of the arm *n*⁴ the pawl *n*¹⁰ is thrown upward by the lever-arm *n*⁵ and the link *n*¹¹ onto the periphery of the disk *n* and abutting against one of the peripheral stop-pins *n'* to prevent further rotation of the disk. The gravity-pawl *n*³ also slips into place back of one of the pins *n'* to prevent a back movement of the disk *n*, and the disk is locked in its stationary position by the two pawls. The lever-arm *n*⁵, when used in connection with the flat strip *n*¹², serves also to automatically magnetize and demagnetize the magnet *n*⁹ by making and breaking the circuit in which it is included, as follows:

In the diagram illustrated in Figs. 2 and 3 one wire *n*¹³ of the electromagnet *n*⁹ is connected directly with one pole of the battery *n*¹⁴ or other source of electric energy, while the other wire *n*¹⁵ of said magnet is connected with a hook-shaped contact-piece *n*¹⁶, carried on the end of the arm *n*⁵. The other pole of the battery *n*¹⁴ is connected with a thin contact strip or switch *n*¹². This strip *n*¹² has on

its inner surface an insulating or non-conducting block n^{17} , which is slightly shorter than the arc described by the piece n^{16} when moved by the lever-arm n^5 . The strip n^{12} , with the exception of the block n^{17} , is made of copper or other good conducting material, which is slightly resilient and insures good results in practice of the same. The strip n^{12} is sheared, as at n^{18} and n^{19} , to form an overlapping guide or edge above the non-conducting surface n^{17} , the lower edge of the guide extending slightly below the upper edge of the block n^{17} . Whenever the piece n^{16} rests on the conducting portion of the strip n^{12} , the circuit is completed and the electromagnet is energized; but when the piece n^{16} travels on the block n^{17} the current is broken and the electromagnet is demagnetized. When the arm n^5 is under the influence of its spring n^7 and is elevated thereby, the contact-piece n^{16} travels upward over the block n^{17} until it comes into contact with the overlapping guide, when the current is completed and the electromagnet is energized. The electromagnet then depresses the lever-arm n^5 by attracting the armature secured thereon, and the piece n^{16} is carried downward over the contact-surface of the strip n^{12} until it clears the lower edge of the strip, when the current is broken and the arm n^5 is free to be raised by the spring n^7 . When the arm n^5 moves upward over the non-conducting surface n^{17} , under the influence of the spring n^7 , the end of the contact-strip is swung slightly to the left by the hook-shaped contact-piece n^{16} until this contact-piece n^{16} is opposite the sheared portions n^{18} and n^{19} , when the resiliency of the strip n^{12} will cause it to spring to the right until the hook n^{16} rests against the overlapping portion of said strip n^{12} . A contact is thereby established, and the hook will be moved downward over the contact-surface of the strip n^{12} against the influence of the spring n^7 , which at the same time is drawn slightly to the right. When the hook n^{16} clears the lower end of the strip n^{12} , the same will spring back slightly to the left, thus presenting the non-conducting face n^{17} to the hook n^{16} . The circuit being thus broken, the spring n^7 will lift the hook n^{16} upward over the non-conducting face n^{17} . The successive positions of the strip n^{12} are illustrated in full and dotted lines in Fig. 3 of the drawings.

In operation the magnet n^9 is connected with the battery n^{14} and is thereby magnetized. The armature n^8 is attracted to the magnet against the influence of the spring n^7 . The lever-arm n^5 and its link n^{11} are thus moved downward, thereby bringing pawl n^{10} into alignment with the pins n' . The hook-shaped arm n^4 is moved downward by the lever-arm n^5 and strikes against one of the actuating-pins n^2 before the pawl n^{10} is in the path of pins n' . The disk n is thus rotated through the shaft c , to which said disk is se-

cured. The sign e is also rotated a sufficient distance to present one of its four faces to the observer. During the downward movement of the lever-arm n^5 its hook n^{16} is in contact with the conducting-face of the strip n^{12} , so that the current from the battery n^{14} continues to flow through the magnet n^9 and to energize the same. When, however, the lever-arm n^5 has reached its lowest position, (indicated by dotted lines in Fig. 2,) the hook-shaped arm n^4 has completed its stroke and the hook n^{16} reaches the position indicated in dotted lines in Fig. 3, in which it clears the contact-strip n^{12} . At this moment the strip n^{12} springs to the left, as shown in dotted lines in Fig. 3, and the current through the magnet is broken. The spring n^7 now forces the armature n^8 upward away from the magnet n^9 , and also forces the lever-arm n^5 upward. The movement of the arm n^5 is transferred through link n^{11} to the pawl n^{10} , which is thrown out of alignment with the stop-pins n' . A gravity-pawl n^3 prevents a rebound or backward movement of the disk c . In its upward movement, under the tension of spring n^7 , the arm n^5 carries its hook-shaped end n^{16} upward along the non-conducting face n^{17} of strip n^{12} , thus forcing the strip to the left, as indicated in dotted lines in Fig. 3. When, however, the hook n^{16} reaches the sheared portion n^{18} , the strip n^{12} will spring to the right to the position indicated in full lines in Figs. 2 and 3, and the hook n^{16} will then contact with the conducting portion n^{19} of strip n^{12} .

Having thus described the nature and objects of my invention, what I claim as new, and desire to secure by Letters Patent, is—

1. The combination of a rotatable sign, a shaft carried by the sign, a disk secured to said shaft, an electromagnet, an armature therefor, a circuit making and breaking device for energizing and de-energizing said magnet, consisting of a flexible contact-strip and a lever-arm traversing the same carried by the armature, and mechanism controlled by said lever-arm for rotating said disk, substantially as and for the purposes described.

2. The combination of a rotatable sign, a shaft carried by the sign, a disk secured to said shaft, an electromagnet, an armature therefor, a lever-arm carried by said armature, a hook carried by said lever-arm, a flexible contact-strip traversed by said hook and adapted to thereby make and break the magnetizing-circuit, and mechanism controlled by said lever-arm for rotating said disk, substantially as and for the purposes described.

In testimony whereof I have hereunto set my signature in the presence of two subscribing witnesses.

MANLY M. GILLAM.
